TOOTHBRUSH COVER

Seymour F. Fohrman, 8242 McCormick Blvd.,
Skokie, Ill. 60076

Filed Aug. 25, 1969, Ser. No. 18,847

Term of patent 3½ years

Int. Cl. D4—02

U.S. Cl. D4—18

Fig. 3.

Fig. 4.

Fig. 5.

Fig. 6.

Fig. 7

FIG. 1 is a perspective view of a toothbrush cover in closed condition, showing my new design. The broken lines are shown for illustrative purposes only and form no part of the claimed design.

FIG. 2 is a top plan view of the same;

FIG. 3 is an end view of the same as viewed from the left of FIG. 1;

FIG. 4 is an end view of the opposite end thereof;

FIG. 5 is a plan view as seen in the direction of line 5—5 of FIG. 2;

FIG. 6 is a plan view as seen in the direction of 6—6 of FIG. 2;

FIG. 7 is a perspective view thereof in open condition.

I claim:

The ornamental design for a toothbrush cover, as shown and described.
